FLUID PRESSURE DEVICE

Ellery R. Fitch, Elyria, Ohio, assignor to Bendix-Westinghouse Automotive Air Brake Company, Elyria, Ohio, a corporation of Delaware

Application April 30, 1943, Serial No. 485,225

16 Claims.

(Cl. 121—38)

This invention relates to control mechanisms and more particularly to remotely controlled fluid pressure operated mechanisms especially adaptable for use in connection with the control of throttle valves on motor vehicle engines.

It has heretofore been proposed to employ fluid motors of the type having cylinders and pistons for actuating such throttle valves by fluid pressure, but due to the inherent friction between the piston and the cylinder walls, considerable difficulty has been experienced in obtaining smooth and satisfactory control.

It is accordingly an object of the present invention to provide a fluid motor for actuating such mechanisms so constituted as to avoid the above disadvantages.

Another object of the invention is to provide, in a fluid motor of the above type, an arrangement for providing smooth and efficient action throughout the entire range of operation.

Yet another object of the invention is to provide, in a fluid motor of the above type, resilient means for opposing movement of the piston so constituted as to permit the rate of pickup of the resilient means to be increased and decreased as desired during different portions of the piston stroke.

A further object of this invention is to provide, in a fluid motor of the above type, means for insuring a greater travel during the latter portion of the piston stroke during a given pressure increase than occurs during a like pressure increase on the piston during the first part of the stroke.

Still another object of the invention is to provide, in a fluid motor of the above type, resilient means for opposing movement of the piston, so constituted as to provide a high rate of pickup of the resilient means during the initial portion of the stroke and a lower rate of pickup during the balance of the stroke.

These and other novel objects and features of the invention will become more readily apparent when considered in the light of the drawing and the following description.

In order that those skilled in the art may fully understand the nature of the present invention and its application to vehicle controlling members, and particularly to the control of vehicle engine throttle valves, two modifications have been set forth hereinafter by way of description and exemplification in the accompanying drawing. It is to be expressly understood, however, that the drawing is employed for purposes of illustration only, and is not designed as a defini-

tion of the limits of the invention, reference for this purpose being had to the appended claims.

In the drawing wherein similar reference characters refer to similar parts throughout the several views;

Fig. 1 is a diagrammatic view, partially in section, of a control mechanism constructed in accordance with the principles of the present invention, and

10 Fig. 2 is an axial sectional view of a modified form of a fluid motor adapted to be employed in the system illustrated in Fig. 1.

Referring more particularly to Fig. 1, the system illustrated includes a source of fluid pressure or reservoir 5 adapted to be supplied with fluid pressure from a suitably driven compressor 6, through the medium of a conduit 7, fluid pressure being supplied from the reservoir 5 under the control of the operator to a fluid motor, generally designated as 8, through the medium of a conduit 9, a control valve 10, and a conduit 11 leading therefrom to the fluid motor.

The control valve 10 is provided with an operating pedal 12 and an exhaust port 13, the 25 valve preferably being constructed as shown in Fig. 1 of the patent to William J. Andres and Roy S. Sanford, No. 2,133,275, dated October 18, 1938, it being understood that this valve is of the so-called self-lapping type, and that the graduating spring of the valve is preferably preloaded in order to provide an initial predetermined output pressure on initial operation of the control pedal 12, and to provide additional increments of output pressure on further operation of

35 the control pedal which are proportional to the degree of movement of the control pedal. It will be further understood that with the control pedal in the position shown, the valve mechanism serves to establish a connection between conduits 40 11 and 13 to connect the fluid motor with atmosphere and to prevent communication between the conduits 9 and 11, while on downward movement of the control pedal, the valve prevents communication between the conduit 11 and the exhaust port 13 and establishes a connection between conduits 9 and 11 in order to supply fluid pressure to the motor 8 from the reservoir 5.

In the drawing, the fluid motor 8 is adapted to control the operation of an engine 14 provided with an inlet manifold 15 and a throttle valve 16 pivotally mounted therein by means of a shaft 17, the shaft being provided with a throttle operating lever 18 as shown. This lever is actuated by means of the fluid motor 8 as will be described hereinafter, the motor 8 being provided with a

cylindrical casing 19, the right end of the casing being connected to the conduit 11 through suitable ports 20 formed in the end of the casing, and the left end of the casing being closed by means of a suitable plate 21. A bore 22 is centrally located in the plate and serves to guide a connecting member or rod 23 slidably mounted therein and connected at its left end to the lever 18 by means of a pivot pin 24 engaging a slot 25 in the lower end of the lever. In order that the throttle may be normally maintained in closed position, a retracting spring 26 is interposed between the right face of the plate 21 and the left face of a shoulder 27 formed on the rod 23, this arrangement serving, in connection with a stop 28 formed on the connecting rod and abutting the left end of the plate 21, to preload the spring 26 in order to normally maintain the connecting rod in retracted position with a predetermined degree of force depending on the degree of compression of the spring.

A piston 29 is slidably mounted in a bore 30 formed in the casing 19, and is adapted to impart motion to the connecting rod 23 through the medium of a spring 31 interposed between the right side of the shoulder 27 and the left face of plate 32 carried by an extension 33 formed on the piston. An extension 34 of reduced diameter is formed on the right end of the connecting rod 23 which is slidably mounted in a bore 35 formed in the extension 33, separation of the parts being prevented by means of a pin 36 mounted in the right end of the extension 34 and adapted to slide in slots 37 formed in the extension 33. The pin 36 is so located with reference to the parts as to initially pre-compress the spring 31 with a force which may be equal to, but preferably less than, the force exerted by the spring 26 due to the precompression of the latter, the tendency thus being, on application of fluid pressure to the right end of the piston, for the piston to move to the left and partially compress the spring 31 prior to movement of the connecting rod 23. The piston is provided with a sealing member or cup 38, and it will be understood that movement of the piston is normally opposed by a force corresponding to the friction between the piston 29 and the wall of the cylinder as well as by a force due to the friction of the sealing member 38 on the cylinder wall, and the degree of preloading or precompression of the spring 31 is preferably so chosen as to be less than the preloading of the spring 26 and slightly greater than the total frictional force opposing initial movement of the piston, the spring 26 thus acting to normally maintain the rod 23 in the retracted position shown, and the spring 31 serving to maintain the piston in the position shown with the pin 36 in the left end of the slots 37.

As heretofore stated, the control valve 10 is of the preloaded type, initial operation of the control pedal 12 serving to immediately supply a predetermined pressure to the casing 19, and the preloading of the valve 10 is preferably so arranged as to initially admit to the casing a pressure which, acting on the area of the piston 29, is just sufficient to overcome the force exerted by the preloaded spring 26, initial operation of the pedal 12 thus tending to result in immediate slight movement of the connecting rod 23 to the left to initially operate the throttle valve, the application of pressure to the casing 19 thereafter directly being proportional to the degree of further movement of the pedal 12.

In view of the relationship of the force initially exerted by the springs 26 and 31 it will be understood that on application of pressure to the casing sufficient to just overcome the tension of the spring 26, this pressure will also be sufficient to overcome the friction of the piston and sealing cup as well as the tension of the spring 31, in order to permit the piston to immediately move to the left with relation to the connecting member 23, and since the friction of motion of a piston of this type is normally less than the static friction, it will be apparent that after initial movement of the piston, this friction will decrease and the piston will respond with greater sensitivity to additional increments of pressure supplied to the casing. Thus the piston will be in motion before movement of the connecting rod 23 to the left occurs, and the initial jerk which often occurs in mechanisms of this kind when the piston tends to stick in retracted position, will be substantially eliminated. Likewise, in the event the piston tends to move rapidly to the left as soon as the frictional force is overcome, the spring 31 will tend to absorb the shock which would otherwise be imparted to the rod 23 when this action occurs, thus preventing erratic operation of the throttle valve of the engine. It will also be understood that the dimensions of the spring 31 may be so chosen in relationship to the dimensions of spring 26 as to permit the spring 31 to be effective throughout the entire range of movement of the connecting rod 23 and the piston 29 in order to provide a resilient connection between the piston and rod at all times. In the event this action is not desired in a particular installation, the spring 31 may be so constructed as to permit the plate 32 to engage the shoulder 27 when the valve 10 is operated to initially supply fluid pressure to the casing 19, in order to provide a so-called hammer action on the connecting rod 23 in order to overcome any slight friction which may exist in the operation of the connecting rod or the throttle mechanism connected thereto. With regard to the desirability of preloading the spring 31 sufficiently to overcome the friction of the piston and sealing cup, it will be seen that this is necessary in order to insure that the piston will always return to the position shown in the drawing on release of fluid pressure from the casing 19.

In connection with the construction of a fluid motor such as shown in Fig. 1, it has been found desirable in the past under certain conditions of operation, to provide means for increasing the rate at which the retracting spring force increases after the piston has travelled through a predetermined distance, and this has been accomplished by the use of additional springs so constituted as to be picked-up by the piston or connecting rod after the predetermined travel has occurred, the result being that during the initial portion of the stroke the rate of spring force increase is that of the first spring while the rate during the latter portion of the stroke is the combined rate of both springs. It is pointed out, however, that a reverse action can be obtained wherein the rate of force increase of the retracting spring mechanism is greater during the initial portion of the stroke than during the latter portion of the stroke, and another embodiment of the invention is illustrated in Fig. 2, so constituted as to provide this desirable type of operation.

As shown in the drawing, this alternative form

of fluid motor is provided with a casing 18 connected at its right end with conduit 11 through the medium of ports 20 and closed at the left end by means of a plate 21 having a connecting rod 23 slidably mounted in the bore 22, the left end of the rod being connected for actuation of the throttle valve 16 in the same manner as shown in Fig. 1. The motor is likewise provided with a piston 28 connected with the rod 23 through the medium of a lost motion mechanism identical with that shown in Fig. 1, as well as through the medium of a spring 31, likewise arranged in the same manner as in Fig. 1.

In order that the connecting rod may be normally maintained in retracted position, a plate 27 is mounted on the connecting rod, and a second plate 39 is carried by the casing 18, as shown, and provided with a centrally located bore 40 for permitting unobstructed movement of the connecting rod, movement of the plate 39 to the right being prevented by means of a shoulder 41 formed in the casing. A spring 42 is interposed between the plate 21 and the plate 27 tending to force the rod 23 to the right, and a spring 43 is interposed between the plate 27 and the plate 39 tending to move the rod 23 to the left, the relationship of these springs being such that the rod 23 is normally maintained in the position shown with both of the springs partially compressed.

As has been heretofore stated, the rate of spring force increase during movement of the connecting rod 23 to the left in the event the spring 42 only were used to position the connecting rod, would be the rate of the spring 42, but it has been found that when this spring is opposed by the spring 43, with both of the springs in a compressed state, the effective spring rate is the sum of the rates of change in force of the two springs. The spring 43 is so dimensioned, however, as to be fully extended when the connecting rod has moved to the left through a predetermined distance, the spring thus being ineffective to impart force to the connecting rod through plate 27 during further travel of the connecting rod, thus providing a construction wherein the rate of change of force exerted by the spring system is greater during the initial part of the stroke than it is during the balance of the stroke, since the force exerted by one spring is decreasing as the force exerted by the other increases, the result being that the degree of travel of the connecting rod in response to a predetermined pressure increase in the casing during the initial portion of the stroke is less than the travel of the connecting rod during the latter portion of the stroke in response to an equal increase in pressure in the latter range. It will be apparent that the spring 43 can be so designed as to become ineffective at any desired point in the stroke.

By combining a plurality of springs in the manner indicated in the drawing, the rate of force change of the spring system may be varied as desired during different portions of the stroke. By way of example, an additional spring 44 may be interposed between the plate 39 and the plate 27 and so dimensioned as to become ineffective before the spring 43 becomes ineffective, thus providing an additional step at which the rate of the spring system is different from that occurring either during the first or the last portion of the stroke. If desired, the action of the spring system may be varied by a further spring 45 which may have a different rate from any of the other springs, and if it is desired to subsequently in-

crease the rate of the spring system after the connecting rod has moved through a predetermined distance, an additional spring 46 may be provided, so dimensioned as to be picked-up by the plate 27 after the piston has travelled through a predetermined distance in order to again increase the spring system rate. As indicated in the drawing, another spring 47 may be interposed between plates 27 and 30 having still different characteristics from the springs 43 and 44, various combinations of the above springs arranged on either side of the plate 27 with varying degrees of compression, varying lengths and varying rates providing any desired rate of force change in the spring system during any portion of the connecting rod stroke.

As heretofore stated, the connecting means between the piston 28 and the connecting rod 23 is arranged in the same manner as shown in Fig. 1, and for the same purpose, and in order to provide the same type of operation and to obtain the advantages inherent in this arrangement, the springs 42, 43, 44, 45, 46 and 47 are so arranged as to resist initial movement of the connecting rod to the left with a predetermined force, the spring 31 being preferably preloaded so as to prevent relative movement of the piston and connecting rod with an equal or lesser force. In addition to this, it is understood that the force exerted by the spring 31 to oppose relative movement of the parts in the position shown, is preferably slightly in excess of the friction force opposing initial movement of the piston 28 on application of fluid pressure thereto, for the same reasons stated in connection with Fig. 1.

It will be readily apparent from the foregoing description, that fluid pressure control mechanism of novel design has been provided, wherein the fluid motor is so constituted as to overcome or minimize the effects of piston friction, and further so constituted as to provide this desirable type of operation under all ordinary conditions of service. As more particularly illustrated in Fig. 2, novel means have also been provided retaining the advantages of the mechanism illustrated in Fig. 1, and at the same time providing a construction having resilient means for normally maintaining the actuating means in retracted position, so constituted as to permit the effective rate of the spring system to either increase or decrease at any desired point in the stroke. While the two described embodiments of the invention have been illustrated as applied to the control of the throttle mechanism of an engine, it will be readily understood that control systems of the type illustrated and described may be readily adapted to the control of other devices if so desired.

While two modifications of this invention have been described and illustrated, it is to be expressly understood that the invention is in no way limited thereby and that various changes and modifications may be made therein without departing from the scope of the invention, for the limits of which reference is had to the appended claims.

What is claimed is:

1. The combination with a source of fluid pressure and a device to be actuated, of a fluid motor having a casing adapted to receive fluid under pressure from said source, a pressure responsive element movably mounted in said casing and subjected to the pressure in said casing, a movable actuating member connected with said device, preloaded resilient means associated with said

member for exerting a predetermined force to normally maintain the latter in retracted position, resilient means for connecting said element and member for permitting relative movement therebetween prior to movement of said member when fluid pressure is supplied to said casing, and means including a substantially frictionless lost motion connection between said member and element for precompressing said second resilient means, whereby the latter opposes relative movement of the member and element with a force less than said predetermined force and greater than the friction force between the element and casing.

2. The combination with a source of fluid pressure and a device to be actuated, of a fluid motor having a casing adapted to receive fluid under pressure from said source, a piston slidably mounted in said casing and subjected to the pressure in said casing, an actuating member connected with said device, preloaded resilient means for normally maintaining said member in retracted position with a force greater than the friction force between the piston and casing, means including a resilient member and a substantially frictionless lost motion connection connecting said actuating member and piston for opposing relative movement therebetween with a force greater than said friction force and less than said first named force.

3. The combination with a source of fluid pressure and a device to be actuated, of a fluid motor having a casing adapted to receive fluid under pressure from said source, a piston slidably mounted in said casing and subjected to the pressure in said casing, an actuating member connected with said device, a preloaded spring interposed between said casing and member for normally maintaining the latter in retracted position with a force greater than the friction force between the piston and casing, a substantially frictionless lost motion connection between said piston and member for freely permitting limited relative movement therebetween, and resilient means interposed between said member and piston for opposing said relative movement with a force greater than said friction force and less than said first named force.

4. The combination with a source of fluid pressure and a device to be actuated, of a fluid motor having a casing adapted to receive fluid under pressure from said source, a piston slidably mounted in said casing and subjected to the pressure therein, and means for connecting said piston and device including a connecting member and means associated with said member and piston for insuring movement of the latter prior to movement of the former when the pressure in said casing exceeds a predetermined value including a preloaded spring interposed between said casing and member for normally maintaining the latter in retracted position with a predetermined force, a preloaded spring interposed between said member and piston for opposing relative movement therebetween with a force less than said predetermined force and greater than the friction force between said piston and casing, and a substantially frictionless lost motion connection between said piston and member for insuring preloading of said second named spring to exert said second named force.

5. The combination with a source of fluid pressure and a device to be actuated, of a fluid motor having a casing adapted to receive fluid under pressure from said source, a piston slidably

mounted in said casing and subjected to the pressure therein, means for connecting said piston and device including a connecting member and means associated with said member and piston for insuring movement of the latter prior to movement of the former when the pressure in said casing exceeds a predetermined value including a preloaded spring interposed between said casing and member for normally maintaining the latter in retracted position with a predetermined force and a preloaded spring interposed between said member and piston for opposing relative movement therebetween with a force less than said predetermined force and greater than the frictional force opposing movement of said piston in said casing, and a substantially frictionless lost motion connection between said member and piston for effecting the preloading of said second named spring.

6. The combination with a source of fluid pressure and a device to be actuated, of a fluid motor having a casing adapted to receive fluid under pressure from said source, a piston slidably mounted in said casing and subjected to the pressure therein, means for connecting said piston and device including a connecting member, means associated with said member and piston for insuring movement of the latter prior to movement of the former when the pressure in said casing exceeds a predetermined value including a preloaded spring interposed between said casing and member for normally maintaining the latter in retracted position with a predetermined force and a preloaded spring interposed between said member and piston for opposing relative movement therebetween with a force less than said predetermined force, and valvular means for controlling the pressure supplied to said casing from said source having a controlling element operable on initial movement to supply a pressure to said casing sufficient to move said piston against said lesser force and operable on further movement to increase the pressure in said casing in direct proportion to the degree of said further movement.

7. The combination with a source of fluid pressure and a device to be actuated, of a fluid motor having a casing, a piston slidably mounted in said casing and subjected to the pressure of fluid therein, means for connecting said piston and device, resilient means for maintaining said piston in retracted position with a predetermined force, and resilient means effective through a portion of the stroke for opposing a portion of the force exerted by said first named resilient means and ineffective during the balance of the stroke, whereby the fluid pressure necessary to move the piston during the first portion of the stroke is proportional to the combined pick-up of the two resilient means and is proportional to the pick-up of the first named resilient means during the latter portion of the stroke.

8. The combination with a source of fluid pressure and a device to be actuated, of a fluid motor having a casing, a piston slidably mounted in said casing and subjected to the pressure of fluid therein, means for connecting said piston and device, a spring for maintaining said piston in retracted position with a predetermined force and for opposing movement of the piston in one direction throughout the entire piston stroke, and a second spring tending to move the piston in the opposite direction during a portion of the stroke with a force initially equal to or less than said predetermined force, whereby the pressure

increment in the casing necessary to move the piston a predetermined distance during said portion of the stroke is greater than that necessary to move the piston through the same distance during the balance of the stroke.

9. The combination with a source of fluid pressure and a device to be actuated, of a fluid motor having a casing, a piston slidably mounted in said casing and subjected to the pressure of fluid therein, means for connecting said piston and device, and a pair of opposed preloaded springs associated with said casing and piston for opposing movement of the latter in one direction by a force corresponding to the difference in the forces exerted by the two springs, one of the springs being effective throughout the entire piston stroke and the other being effective during a portion of said stroke.

10. The combination with a source of fluid pressure and a device to be actuated, of a fluid motor having a casing, a piston slidably mounted in said casing and subjected to the pressure of fluid therein, means for connecting said piston and device, means for supplying desired equal increments of pressure to said casing and piston, and means for progressively increasing the movement of said piston in response to said equal pressure increments including a plurality of opposed springs interposed between the casing and connecting means, the springs acting in one direction being effective during the entire piston stroke and the springs acting in the opposite direction being effective during a portion of the stroke.

11. The combination with a source of fluid pressure and a device to be actuated, of a fluid motor having a casing, a piston slidably mounted in said casing and subjected to the pressure of fluid therein, an actuating member having a connection with said device, resilient means interposed between said casing and member for exerting a predetermined force thereon for maintaining the member in retracted position and for opposing movement thereof through the entire stroke, resilient means interposed between the casing and member for exerting a lesser force on the member in the opposite direction during a portion of the stroke, and means for connecting said member and piston including a spring for opposing initial relative movement therebetween with a force less than the difference in the two first named forces.

12. The combination with a source of fluid pressure and a device to be actuated, of a fluid motor having a casing, a piston slidably mounted in said casing and subjected to the pressure of fluid therein, and means for opposing movement of said piston during one portion of the travel thereof, with a force increasing at a predetermined rate and during an additional portion of the travel with a force increasing at a lesser rate including a spring interposed between the piston and casing for opposing movement thereof on application of fluid pressure to said casing, and a second spring interposed between said piston and

casing for assisting said movement during said one portion of the travel.

13. A fluid actuator comprising a cylinder, a piston slidably mounted in said cylinder, a piston rod slidably mounted in the cylinder, a preloaded spring interposed between the cylinder and rod for normally maintaining the latter in retracted position in the cylinder with a predetermined force greater than the normal friction force between the piston and cylinder, and means connecting said piston and rod for normally maintaining the piston in retracted position relative to the rod and for insuring initial movement of said piston prior to movement of said rod in response to the application of fluid pressure to the cylinder including a spring interposed between the piston and rod and a substantially frictionless lost motion connection between said rod and piston for preloading the second named spring to normally maintain the piston in said retracted position with a force less than that exerted by the first named spring on the rod and greater than the normal friction force between the cylinder and piston.

14. A fluid actuator comprising a cylinder, a piston slidably mounted therein, and means for opposing movement of said piston during one portion of the travel thereof with a force increasing at a predetermined rate and during an additional portion of the travel with a force increasing at a lesser rate including a spring interposed between said casing and piston for opposing movement thereof on application of fluid pressure to the cylinder, and a second spring interposed between the piston and casing for assisting said movement during said one portion of the travel.

15. A fluid actuator comprising a cylinder, a piston slidably mounted in the cylinder, a piston rod in the cylinder, resilient means interposed between the cylinder and rod for exerting a predetermined force thereon in one direction for normally maintaining the rod in retracted position and for opposing movement thereof during the entire stroke, resilient means interposed between the cylinder and rod for exerting a lesser force on the rod in the opposite direction during a portion of the stroke, and means for connecting said rod and piston including a spring for opposing initial relative movement therebetween with a force less than the difference in the two first named forces.

16. A fluid actuator adapted to receive equal increments of fluid pressure comprising a casing, a piston slidably mounted in said casing, and means for progressively increasing the movement of said piston in response to said equal fluid pressure increments including a plurality of opposed springs interposed between said casing and piston, the springs acting in one direction being effective during the entire piston stroke and the springs acting in the other direction being effective during portions of the stroke.
